(57) **CLAIM**

The ornamental design for a ceiling lamp, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front and left side isometric view of a ceiling lamp;

FIG. 2 is a rear and right side isometric view thereof;

FIG. 3 is a front elevation view thereof;

FIG. 4 is a right-side elevation view thereof, the left-side view being a mirror image of the right-side view;

FIG. 5 is a rear elevation view thereof;

FIG. 6 is a top view thereof; and,

FIG. 7 is a bottom view thereof.

The drawings include surface shading that represents contour and not surface ornamentation.

The broken lines in the drawings depict parts of the article that form no part of the claimed design.
